(57) **CLAIM**

The ornamental design for a boot, as shown and described.

DESCRIPTION

FIG. 1 is a perspective view of the boot.

FIG. 2 is a front elevational view of the boot; and,
FIG. 3 is a side elevational view of the boot with the
opposite side being a mirror image of the same.

The top, bottom and back of the boot form no part of the
claimed design.

The broken lines form no part of the claimed design.
